(57) **CLAIM**

The ornamental design for a panel for an audio-video device, as shown and described.

DESCRIPTION

A portion of this patent document contains material which is subject to copyright protection. This patent document may show and/or describe matter which is or may become trade dress of the owner. The copyright and trade dress owner has no objection to the facsimile reproduction by any one of the patent disclosure as it appears in the Patent and Trademark Office patent files or records, but otherwise reserves all copyright and trade dress rights whatsoever.

FIG. 1 is a front perspective view of a panel for an audio-video device showing my new design;

FIG. 2 is a front perspective view thereof, shown in it's environmental use;

FIG. 3 is a front elevational view thereof; and,

FIG. 4 is a front elevational view thereof, shown in it's another environmental use.

The broken lines environmental are for illustrative purpose only and form no part of the claimed design.
